(57) **CLAIM**

The ornamental design for a portable floor scale with a display as shown and described.

DESCRIPTION

Figure 1.1: Front perspective view of a portable floor scale with display;

Figure 1.2: Top view thereof;

Figure 1.3: Left side view thereof;

Figure 1.4: Bottom view thereof;

Figure 1.5: Right side view thereof;

Figure 1.6: Rear view thereof;

Figure 1.7: Front view thereof, and

Figure 1.8: Rear perspective view thereof.

The broken lines show portions of the portable floor scale with a display that forms no part of the claimed design. The bottom of the portable floor scale with a display as defined by Figure 1.4 forms no part of the claimed design.
